Elmer J. Ney, of Lowell, Mass.

Assignor to
The Lowell Manufacturing Company,
Letters Patent No. 1641, dated Aug. 12, 1862,

The schedule referred to in these Letters Patent and making part of the same,
To all whom it may concern;

Be it known that I, Elmer J. Ney, of Lowell, in
the County of Middlesex and State of Massachusetts, have originated
and designed a new Pattern for Carpets or other fabrics, of which the fol-
lowing is a full, clear and exact description, reference being had to
the accompanying drawings, making part of this specification.

In corner A, is one fourth of a many sided block,
surrounded by small leaves resting on the dotted ground, 1, which
has an edge of short straight lines running at various angles with
each other. The frame 2, encloses the ground, 1. The figures of corner
B, are similar to those of corner A, and rest on the dotted ground 3, this
ground is enclosed by the frame 4. Lying between the frames 2, and
4, are the irregular figures 5 and 6, which are composed of a network
of diamonds and crosses enclosed by solid lines.

The colors employed for the different portions of the de-
